(57) **CLAIM**

The ornamental design for a temperature therapy device, as shown and described.

DESCRIPTION

The FIGURE is a top plan view of a temperature therapy device showing the new design.

Structure illustrated in broken lines is provided to illustrate the environment of the invention but is not otherwise part of the claimed design. Portion(s) of the temperature therapy device that would normally be visible, but are not shown in the drawing or described in the specification, are not part of the claimed design.
